UNITED STATES PATENT OFFICE.

VEON I. MONCRIEFF, OF INDIANAPOLIS, INDIANA.

INTERNAL-COMBUSTION ENGINE.

1,374,313.

Specification of Letters Patent. Patented Apr. 12, 1921.

Application filed June 7, 1920. Serial No. 386,958.

To all whom it may concern:

Be it known that I, VEON I. MONCRIEFF, a citizen of the United States, residing at Indianapolis, in the county of Marion and 5 State of Indiana, have invented a new and useful Internal-Combustion Engine, of which the following is a specification.

The object of my invention is to provide certain improvements in internal combustion engines, whereby a scavenging charge 10 of air may be caused to drive out the products of combustion from the work chamber and be followed by a charge of fuel under pressure.

15 The accompanying drawings illustrate my invention. Figure 1 is a side elevation of an engine embodying my invention, some of the parts being shown in vertical section; Fig. 2 is an end elevation, some of the parts 20 being shown in vertical section.

In the drawings, 10 indicates a cylinder, 11 a piston, 12 a piston rod, and 13 a crank shaft of ordinary construction.

Each cylinder is provided with normally 25 closed air inlet valve 14 and a normally closed fuel inlet valve 15, each of said valves being conveniently normally closed by a spring 16 opened at the proper time by a cam 17 on a cam shaft 18.

30 At the outer end of each cylinder 10 is an exhaust port 19, which is uncovered and covered by piston 11.

Leading to the several air valves 14 is an air manifold 20, which is connected to an air 35 chamber 21.

The valves 15 are supplied from a fuel manifold 22 connected to a carbureter 23, and air for this carbureter is supplied through a pipe 24 which is connected to an 40 air chamber 25.

In the form shown in the drawings, the two air chambers 21 and 25 are formed in a single hollow casting 26 bolted to the end of the crank case 27 and provided with an 45 internal partition 28 (Fig. 2) which separates the interior into the two chambers 21 and 25.

Leading into chamber 21 are supply openings 30 (dotted lines Fig. 2) and leading 50 into chamber 25 are openings 31. Bolted upon casting 26 is a shell 35 which forms a plurality of pockets, indicated by dotted lines 36 in Fig. 2. These pockets connect with each other, as indicated, and mounted 55 in these pockets are five gears 37, which, between them, form four pumps, two of which

deliver air to the openings 30 into chamber 21 and the other two of which deliver air through openings 31 into chamber 25. One of the gears 37 is attached to crank shaft 60 13 and another of the gears is attached to the cam shaft 18.

For the sake of symmetry, the outer end of shell 35 is closed by a hollow casting 40, similar to casting 26, and through which air 65 is received through openings 42 for delivery to the gear pumps.

In operation, the piston 11 being driven outwardly by an exploded charge, uncovers the exhaust passage 19, and at that moment 70 the appropriate flushing valve 14 is opened and flushing air under pressure, passes from chamber 21 through manifold 20 into the initial end of the cylinder 10, driving the exhaust gases in front of it and toward the 75 exhaust passage 19.

When the piston 11 has started upon its return stroke and preferably slightly before it has closed the exhaust passage 19, the flushing valve 14 is closed and the fuel valve 80 15 is opened, whereupon, air is permitted to flow from chamber 25 through to the carbureter supply pipe 24 into and through carbureter 23 and into and through manifold 22, the fuel inlet valve 15 being held open 85 as long as desired, at least up to the time when the compression produced by the return movement of piston 11 nearly equals the supply pressure in chamber 25.

It will be readily understood that while 90 the specific form and arrangement of air pump shown is very convenient, yet, nevertheless, material modifications of the pump may be made without departing from my invention.

95 I claim as my invention:

1. In an internal combustion engine, the combination with a cylinder and piston, wherein the cylinder is provided with an exhaust port covered and uncovered by the 100 piston, of two inlet valves, means for opening and closing said inlet valves in succession, means for delivering flushing air to one of said valves under pressure, and means for delivering fuel under pressure to the 105 other of said valves.

2. In an internal combustion engine, the combination with a work cylinder of two inlet valves for said cylinder, means for opening and closing said valves in succession, 110 means for exhausting the spent gases at the end of the work stroke, and means for sup-

plying air under pressure to one of the inlet valves and for supplying fuel under pressure to the other of said inlet valves, said fuel inlet valve being opened and closed during each return stroke of the piston.

3. In an internal combustion engine, the combination with the combustion chamber, piston, crank shaft and casing, of a series of intermeshing lobed impellers, one carried by the crank shaft, a casing for said impellers provided with inlet and outlet passages co-ordinated with said impellers, two inlet valves for the combustion chamber, said inlet valve controlling flow of air under pressure from said impellers to the combustion chamber, a second inlet valve controlling flow of fuel to said combustion chamber under pressure introduced by said lobed impellers, and means for successively opening and closing said inlet valve, said means comprising a valve-operating shaft connected to one of said lobed impellers.

4. In an internal combustion engine, the combination with the combustion chamber, piston, crank shaft and casing, of a series of intermeshing lobed impellers, one carried by the crank shaft, a casing for said im-

pellers provided with inlet and outlet passages co-ordinated with said impellers, two inlet valves for the combustion chamber, said inlet valve controlling flow of air under pressure from said impellers to the combustion chamber, a second inlet valve controlling flow of fuel to said combustion chamber under pressure introduced by said lobed impellers, and means for successively opening and closing said inlet valve.

5. In an internal combustion engine, the combination with a cylinder and piston, wherein the cylinder is provided with an exhaust passage at the outer end of the cylinder and with an inlet passage at the inner end of the cylinder, of means for introducing a stream of flushing gas under pressure immediately following initial exhaust, and means for introducing a fuel stream under pressure into the initial end of the cylinder following the inflow of flushing gas.

In witness whereof I have hereunto set my hand at Indianapolis, Indiana, this 3rd day of June, A. D. one thousand nine hundred and twenty.

VEON I. MONCRIEFF.
